HI-LO IGNITER

Louis Lo Fiego and Robert K. Asplund, Newhall, and Rex L. Smith, China Lake, Calif., assignors, by mesne assignments, to the United States of America as represented by the Secretary of the Navy

Filed Sept. 29, 1959, Ser. No. 843,327

2 Claims. (Cl. 102—70)

The present invention relates to igniters and more particularly to a novel igniter for propellant grains and the like.

The present invention comprises a circular container having a base, and a top member provided with a plurality of orifices. At least one squib is located on the inner side of the base member and a gas producing material in intimate contact with the squib substantially fills the container. When the squib is initiated and the gas producing material is ignited jets of flame are emitted from the orifices in the top member. The present igniter provides improved ignition of solid rocket or missile propellants by improved control over the igniter reaction, particularly the high (gaseous) pressure phase of the reaction.

The previous and conventional methods of igniting solid rocket or missile propellants employ thin, weak metal or plastic igniter cases provided with blow-out plugs, discs or members which function at relatively low and uncontrolled pressures, and also permit expulsion of burning and unburnt portions of the igniter charge into the rocket motor chamber. The disadvantages of the previous igniters are lack of control over igniter pressure; tendency to produce ignition shock; and, lack of control over direction and duration of the igniter flame. The present invention overcomes the disadvantages of prior art igniters by restraining initial high igniter pressures within the igniter chamber and venting the igniter flame into a rocket motor chamber at substantially lower pressure. The present invention also prevents ignition shock or initial high pressure peak in the rocket motor chamber; controls the rate of pressure rise in the motor chamber; increases the duration of the igniter flame; controls the direction of the igniter flame; reduces the amount of burning and unburnt igniter material expelled into the rocket motor chamber; controls the reaction, and conserves space by eliminating the need for a small rocket sometimes used inside rocket motors for build-up to ignite propellant grain.

It is an object of the invention to provide a novel igniter for propellant grains and the like.

Another object of the invention is to provide an igniter for improved ignition of solid rocket propellants and the like by improved control over igniter reaction.

Another object of the invention is to provide a novel igniter for reducing ignition shock and preventing excessive expulsion of unburnt igniter material into a rocket motor chamber.

A further object of the invention is to provide a novel igniter which controls the direction and increases duration of the igniter flame.

Other objects and many of the attendant advantages of this invention will become readily appreciated as the same becomes better understood by reference to the following detailed description when considered in connection with the accompanying drawings wherein:

Fig. 1 is a cross-sectional, elevational view of a pre-

2

ferred embodiment of an igniter of the present invention; Fig. 2 is a cross-sectional view taken along line 2—2 of Fig. 1;

Fig. 3 is a perspective view of the embodiment of Figs. 1 and 2.

Referring now to the drawings like numerals refer to like parts in each of the figures.

10 Igniter 16 is constructed of a metal case 12 and closure portion 14 containing igniter squibs 16 and igniter material 18. Case 12 is dish shaped and has recessed portions 20 in the base thereof in which squibs 16 are seated and apertures 22 therethrough through which igniter squib lead wires 24 pass. One or more squibs 16 for initiating the igniter material 18 may be used to suit particular desired conditions. The inner wall of case 12 may be threaded at 26 for holding closure portion 14 in place. Closure portion 14 is threaded on the outer edge 28 thereof and has a solid depending central portion 30 which seats in recess 32 in the base of case 12. Closure 14 is provided with a plurality of apertures 34 through which igniter flame is vented into the propellant chamber of a rocket motor. The number and size of apertures 34 control the pressure and rate of pressure rise.

25 The ring-shaped chamber 36 within the igniter case is filled with igniter material 18. The igniter material 18 may be a solid grain or pellets, Figs. 1 and 2 illustrate pellets as the igniter material. A layer of cement 40 is provided between igniter material 18 and the apertured surface of closure portion 14 and protects the igniter material 18 from the outside atmosphere. The casing may vary somewhat in assembly construction but preferably should have substantially the shape as illustrated in the drawings.

30 The igniter case is constructed of metal of sufficient thickness and strength to withstand pressures up to 10,000 p.s.i. without rupture and is provided with a predetermined number and size of vent holes which permit passage of the igniter flame to a rocket motor chamber at a controlled pressure and rate of pressure rise. The igniter material 18 in ignition chamber 36 when initiated by ignition elements or squibs 16 creates high pressure igniter flame within the chamber. The igniter flame pressure is around 6,000 to 7,000 p.s.i. The initial high pressure resulting from initiation of the igniter charge within chamber 36 is confined within the igniter case and flame passes to the propellant chamber of a rocket motor at a substantially reduced pressure, which as previously stated, is determined by the number and size of vent holes 34. 40 Since the device is a pressure vessel, enough vent holes 34 must be provided to prevent bursting of the case. By providing a plurality of small vent holes 34 the amount of incompletely burnt igniter material 18 expelled from chamber 36 is greatly reduced, and the duration of the flame is increased. The vent holes also serve to control the direction of the flame toward a rocket motor propellant grain. The direction of some of the vent holes may be varied slightly if it is desired to change the direction of some of the flame jets.

45 50 55 Obviously many modifications and variations of the present invention are possible in the light of the above teachings. It is therefore to be understood that within the scope of the appended claims the invention may be practiced otherwise than as specifically described.

60 65 What is claimed is:

1. A propellant igniter for preventing initial high pressure peak and controlling the rate of pressure rise in a rocket motor chamber, comprising a container having an opening at one end and including a bottom interior surface and a side interior surface, a closure member including a flat portion and a solid portion connected to and extending in a right angle direction from the plane surface

of said flat portion, said flat portion having a plurality of orifices formed therein and the outer periphery thereof disposed in sealing engagement with said opening, the extended portion of said solid cylinder extending into said chamber and spaced from said side interior surface and in fixed sealing engagement with said bottom interior surface thereby forming an annular space between said solid portion, said side interior surface, said bottom interior surface and said flat portion having a plurality of orifices, said annular space being substantially filled with a gas producing material, means positioned on said bottom interior surface operable for initiating said gas producing material.

2. A propellant igniter for igniting the solid propellant of a rocket motor, comprising a hollow cylinder having a solid closure at one end and an outlet closure at the other end, a solid cylindrical member concentrically disposed within said hollow cylinder and in sealing en-

gagement with said solid closure and said outlet closure thereby forming an annular chamber, said chamber being filled with a gas producing material, a plurality of means positioned on said solid closure and adjacent said gas producing material for initiating said gas producing material, said outlet closure having a plurality of orifices disposed in the section thereof adjacent said annular chamber.
